PRODUCTION OF AVIATION GASOLINE

Roger H. Newton, Bowling Green, Pa., assignor
to Houdry Process Corporation, Wilmington,
Del., a corporation of Delaware

Application October 21, 1942, Serial No. 462,794

8 Claims. (Cl. 196—52)

1

This invention relates to the production of desirable hydrocarbon materials, including motor fuels and especially base material for use in aviation engines including fighting grade, as well as training and commercial grades of aviation gasoline.

A principal object of the invention is to produce desirable aviation base material from cracked hydrocarbons in the gasoline boiling range. Another object is to produce aviation base stock for 100 octane fighting grade aviation gasoline which will meet both lean mixture and rich mixture requirements, as in the present A. F. D.-1C and 3C tests. Another object is to produce maximum yields of aviation base material from cracked gasolines. Still other objects will be apparent from the detailed description which follows.

While the present invention has application to conversion of all types of cracked gasoline, whether thermal or catalytic, in the production of aviation base stock, it should be understood that the better the cracked gasoline to begin with, the greater benefits accrue from the use of this invention. As a basis for discussion, therefore, it is desirable to consider the characteristics of good cracked gasoline, such as produced by catalytically cracking heavier hydrocarbons over active catalytic material of the silica-alumina type, whether the catalyst be produced by chemical treatment of naturally occurring clays or by coprecipitation of silica-alumina compounds to produce synthetic catalytic masses. Analysis and study of the components of such a catalytically cracked gasoline having an end point of approximately 450° F. indicates that the olefins are generally undesirable because of low clear octane value and low lead susceptibility. The naphthenic C₈'s and C₉'s are in general acceptable as having a moderately high clear octane and excellent rich mixture characteristics, although of low lead susceptibility. Naphthenes of seven or more carbon atoms are undesirable due to low octane and low lead susceptibility. Isoparaffins are desirable from the standpoint of stability, lead susceptibility and high lean mixture rating. Straight chain paraffins are of low octane but fortunately are not present in appreciable proportions in catalytically cracked fuels. The aromatics are in general good with respect to rich and lean performance, C₁ aromatics being best, C₂ next and the C₃'s acceptable. The aromatics of C₄ and greater are of lower clear octane, poor lead susceptibility and of only moderate rich mixture characteristics.

The olefins occur predominantly in the low

2

boiling portion of the gasoline cut, namely C₅ and C₆, the C₅ cut boiling in the range of 85° to 120° F. and the C₆ cut boiling in the range of 120° to 190° F. The olefins should be removed, or converted to other more desirable hydrocarbons in the aviation boiling range, which can be effected by rather mild conditions of treatment. The greatest improvement in the cracked gasoline stock, especially from the standpoint of rich mixture performance, is to be effected on the heavier naphthenes and aromatics which occur in the broad boiling range of 180° to 500° F., as for example in a 200° to 450° F. cut. By selecting a cut of this boiling range which may at times be extended profitably to include hydrocarbons boiling between 140° and 500° F. and subjecting it to the action of a synthetic cracking catalyst of high activity and purity under severe or drastic operating conditions, such as temperatures of 820° to 950° F. and superatmospheric pressures up to 150 pounds per square inch gauge and feed rates (liquid volume of charge per volume of catalyst per hour) of about 4:1 to 1:1, the highest grade of aviation base stock is produced. The resulting hydrocarbons in the boiling range of aviation gasoline, if originally from a catalytic cracking operation, will meet both A. F. D.-1C and 3C tests [100.0 and S-1 (or S-2) + 1.25 cc. lead, respectively] with 4 cc. of lead and no alkylate, hydrocodimer, or other special addition fluid, or with very little of the latter. The same treatment of a cut of the same boiling range derived from thermally cracked gasoline will produce aviation stock which readily meets commercial and training grade specifications with the addition of lead alone and usually with small amounts of lead, not exceeding 4 cc. In other words, the base aviation gasoline produced from the drastic treatment of the 200 to 450° cut is of such high quality that it will stand considerable dilution by aviation cuts from straight run gasolines or from the front end cut of the originally cracked material which has been subjected to treatment for removal or conversion of the olefins. In general, the imposed conditions are the more effective the narrower the boiling range of the stock treated. Conversely, the broader the cut treated the more severe the treating conditions must be to produce the desired effect on any one compound or group of compounds. On the contrary, however, the presence of a large proportion of olefins, as by inclusion of the C₅ and C₆ cuts, limits the severity of treat possible due to the tendency of the olefins to deposit coke on the

catalyst, thus overburdening the regeneration part of the cycle.

For a refiner to attain a maximum yield of high grade aviation gasoline from cracked hydrocarbons he should divide the motor fuel into two or more cuts for suitable treatment. The point or points of division focus around the C₅ material in the boiling range of about 130° to 210° F. Hence, if he does not wish to make three cuts roughly as follows—the C₅'s (85-130° F.), the C₆'s (130-210° F.) and the C₇'s-C₁₂'s (210-450° F. or 500° F.), he can throw the C₅ cut either way, that is, either with the C₆'s to give a light cut of the boiling range of 85 to about 210° F., or with the heavier hydrocarbons to make a cut of C₅'s to C₁₂'s boiling from 140 to about 450 to 500° F. In other words the dividing line for the two cuts into which the hydrocarbon charge is divided may be selected, as desired or as found expedient, anywhere within a 100° range as from about 125° F. to about 225° F.

If a C₅ cut is made for the purpose of producing alkylate, then iso-pentane will be required to bring the remaining stock after treatment to the proper boiling range. On the other hand, there is usually a shortage of iso-pentane and it is often desirable to treat the C₅ cut in a manner to produce iso-pentane. To attempt to do this on C₅'s alone involves difficulty since they are hard to condense; therefore, it is better to take the C₅'s and the C₆'s together to form a lower boiling cut in the range of 85 to about 200° F. Iso-pentane can be produced by treating this cut under mild cracking conditions, such as temperatures of 750 to 825° F., superatmospheric pressure up to about 50 lbs. per square inch gauge, and feed rates (liquid volume of charge per volume of catalyst per hour) of 1:1 to 3:1 over a high activity catalyst of the silica-alumina type, preferably synthetically produced and of high purity, the operating periods not exceeding 30 minutes and being usually less than 20 minutes followed by regeneration of the catalyst. This treatment removes the olefins in the light cut by converting them to more desirable hydrocarbons in the gasoline boiling range. If production of iso-pentane is not required, other suitable or lower temperature treatments of the light cut may be utilized to remove the olefins by polymerizing the same into higher boiling hydrocarbons outside the aviation range and in the motor naphtha range or heavier. The high temperature treatment is usually preferable because it not only produces the iso-pentane but retains the material present as olefins in the aviation gasoline by converting them into more stable hydrocarbons.

It is important that the original charge to the initial cracking step which precedes the cracked gasoline treatments contain no hydrocarbons boiling below the end point of the aviation gasoline which is to be produced. It is also desirable that the higher boiling cut of cracked gasoline which is selected for drastic treatment, as in the 200 to 450° F. boiling range, be low in olefins since these are converted to coke and may unduly limit the onstream periods over the high activity treating catalyst. For most operations the olefins in this cut should not exceed 10% either by weight or volume.

In order to illustrate the invention and the manner of its use one concrete embodiment of apparatus for conducting the entire operation, including the initial cracking step, is disclosed diagrammatically in the accompanying drawing.

The charging stock which may consist of crude

hydrocarbons higher boiling than aviation gasoline is charged by line 1 to still 2 where the same is vaporized and sent under cracking conditions to and through a reactor 3, which may be of any suitable or desired type, but it is preferably a catalytic reactor of either the static or fluid type charged with cracking catalyst of any known or desired type. The products of the cracking reaction pass by line 4 to fractionator 5 for separation into a bottom or fuel oil cut which leaves the fractionator by line 6, a side-stream cut which leaves by line 7 and an overhead cut which leaves fractionator 5 by line 8. The overhead fraction comprising light hydrocarbons through C₅ or C₆ passes through a condenser 9 and thence into a separator 10 from which fixed gases escape by line 11, and water (if any be present) by line 12, and hydrocarbons by line 13. The hydrocarbons pass through heater 14 and thence to a suitable reactor 15, preferably catalytic, where olefins are removed by conversion or by polymerization, the products leaving reactor 15 by line 16. In the meantime, the next lighter hydrocarbons down to or through C₁₂ pass by line 17 through vaporizer 18 and thence into reactor 19 where they are subjected to drastic cracking conditions over high activity cracking catalyst, the products leaving reactor 19 by line 18. The products of reactors 15 and 19 may be withdrawn separately through lines 20 and 21, respectively, or they may be fed by lines 22 and 23 into the same fractionator 24. An overhead fraction, cut to the end point of the desired aviation gasoline, passes by line 25 through condenser 26 and separator 27 and thence by line 28 to storage at 29. A heavier fraction such as motor naphtha with an end point of about 410° F., for example, leaves fractionator 24 by line 30 as a side stream fraction passing through cooler 31 and thence into storage at 32. Higher boiling material which is highly aromatic in character and hence useful for solvent purposes, as fuel oil, or as cracking stock for producing more aromatics is withdrawn from the fractionator 24 by one or more side stream lines, such as 33, as well as by bottom line 34 leading to storage at 35.

It is to be understood that only the most essential pieces of equipment are indicated in the drawing and then only diagrammatically; auxiliary equipment such as pumps, heat exchangers, regenerating circuits, etc. are omitted since they are not necessary to an understanding of the invention. When static bed reactors are used in the catalytic zones at 3, 15 and 19, a sufficient number of them may be provided to permit continuous operation.

High activity catalysts can be produced from naturally occurring silica-alumina or clay deposits by suitable chemical or other treatment and can be utilized advantageously in both treating zones 15 and 19. However, it is preferable to use silica-alumina catalysts produced synthetically and of low alkali metal content, as for example in accordance with the disclosures of U. S. Patents Nos. 2,283,172 and 2,283,173 issued to J. R. Bates on May 19, 1942, because synthetic catalysts give higher octanes to the treated stocks than do the catalysts produced from clays.

Cracking catalysts other than silica alumina which give excellent results when used for high temperature treatments in accordance with the present invention are highly active compounds of the following: silica-zirconia, silica-alumina-zirconia, silica-alumina-beryllia, etc. The activ-

ity index of the catalysts used should be above about 35, which indicates ability to convert to lighter products at least 35% of a standard reference stock such as East Texas gas oil under standard operating conditions (see page 2, column 1, line 65 through line 39, column 2 of United States Patent No. 2,347,216 issued April 25, 1944 to A. G. Peterkin). In general, on the basis of the activity of the catalyst chosen for the high temperature treatment of the cracked hydrocarbons in the boiling range of about 130 to 500° F. the operating conditions are made more drastic in temperature, pressure or rate, or in all these conditions, than if the identical catalyst were utilized for the initial cracking operation on fresh hydrocarbon charging stock. Pressure of at least 25 lbs. per square inch is utilized in the high temperature treatment of depentanized charging stocks.

When olefins are to be removed from the light cut by polymerization rather than by high temperature conversion, a desirable method is a liquid phase catalytic treatment at relatively low temperatures and under sufficient pressure to maintain liquid phase conditions, as in line with the teaching of U. S. Patent No. 2,273,038 issued February 17, 1942 to E. J. Houdry and J. P. Daugherty, Jr.

The following examples give results typical of various aspects of the invention and show the large percentage of aromatics in the final aviation gasoline stock.

Example 1

A depentanized cracked gasoline in the boiling range of 125° to 400° F. was separated from a cracking operation on 42-88% East Texas crude over synthetic catalyst. This cut was treated under severe conditions as follows:

Rate ..... 0.75:1 (liquid volume of charge to volume of catalyst per hour)
 Temperature ..... 850° F.
 Pressure ..... 50 pounds per square inch gauge
 On-stream period ..... 10 minutes
 Catalyst ..... High activity (39 activity index) synthetic silica-alumina

The resulting products in the aviation gasoline boiling range (90% at 305° F.) was 80.4% by volume of the charge to the operation and had a Reid vapor pressure of 5 pounds. The aromatic content of the depentanized aviation gasoline was 41.2% by volume which was approximately 50% higher than the best present commercial practice with this type of crude as charge. Iso-pentane was added to bring the aviation base stock to 7 pounds. A. F. D.-1C test on the 7 pound material after the addition of 4 cc.'s of tetraethyl lead was 97.3 octane. A. F. D.-3C test with the same quantity of lead gave S₂+2.4 cc.'s of lead. Aromatics in the 7 lb. Reid vapor pressure aviation were 35.3% by volume.

Example 2

A debutanized motor gasoline from the normal cracking of 42-88% East Texas crude was divided into two cuts, the lighter cut being initial to 200° F. and the heavier cut 200-450° F. The cuts were treated separately, the former under mild conditions to remove olefins and the latter under severe

conditions over high activity (41 activity index) synthetic silica-alumina catalyst.

	Initial to 200° F.	200-450° F.
Rate (liquid volume of charge to volume of catalyst per hour)	1.25:1	75:1
Temperature	750	850
Pressure, lbs. per square in. gauge	40	50
On-Stream Period	10	10
Coke, grams per liter of catalyst	6.2	6.7
Yield—overall Aviation, % of charge		
A. F. D.-1C—at 75 R. V. P.+4 cc. TEL	97.2	81.2
A. F. D.-3C—at 75 R. V. P.+4 cc. TEL	S ₂ +1.8 cc. lead	
Aromatics in 7% R. V. P. Aviation	35.3% by volume	

With products of a normal catalytic cracking operation a refiner will usually find it to be desirable to divide the resulting debutanized motor gasoline into two fractions of substantially equal volume. The lower boiling cut beginning with C₅'s and with its end point running up to about 225° F. is more highly olefinic than the heavier cut but contains no undesirable naphthenes or aromatics and its paraffin content is substantially entirely branch-chain material. Thus in substance it requires only a relatively light treating operation to remove or convert the olefins. The higher boiling cut (initial 200 to 225° F. and end point 450° to 500° F.) is predominately aromatic and low in olefins. It is unsatisfactory for inclusion in finished aviation gasoline because of low 1C octane and poor gum stability. Severe treatment of this material overcomes these deficiencies and is possible because of the low olefin content. This treatment is particularly effective because of the high partial pressure which can be obtained on a narrow boiling cut and results in the removal of the olefins and naphthenes and conversion of the aromatics to more desirable aromatics from the standpoint of rich mixture performance.

The present invention discloses methods of producing from cracked hydrocarbons aviation gasolines which meet present day performance tests. In many instances the treatments set forth herein produce aviation gasolines of very high rich mixture performance as well as meeting volatility requirements. With the addition of 4 cc.'s of lead and no alkylate or other addition agent A. F. D.-3C tests of S₂+2 cc. lead have been exceeded (note Example 1 above). East Texas stock has been used in the examples because it is one of the most difficult stocks from which to produce aviation gasoline of acceptable rich mixture rating. More naphthenic stocks give better performance under both 1C and 3C tests and higher yields as well.

It is well known that the 1C test is not an accurate index of the lean mixture performance of a fuel in a full scale engine. In general a finished fuel of the type herein described having a 1C rating of about 97 will give a full scale lean mixture performance equivalent to that of a completely paraffinic fuel having a 1C rating of 100. When the 3C rating of the former is of the order of S₂+1.5 cc. lead or more.

I claim as my invention:

1. Process of making high quality aviation base stock which comprises subjecting cracked hydrocarbons having an end point not exceeding about 500° F. in at least two cuts and under differing operating conditions and separately to treatment by high activity siliceous cracking catalysts, the heavier the cut the more severe the treatment, the temperatures of the treatments being in excess of 750° F. but not in excess of

950° F., segregating hydrocarbons in the aviation gasoline boiling range from the products of said treatments, and combining said segregated hydrocarbons.

2. Process of making high quality aviation base stock which comprises separating cracked hydrocarbons having an end point not exceeding about 500° F. into two cuts, the C₈ hydrocarbons being in either of said cuts, subjecting said cuts separately to the action of high activity silicious cracking catalysts, the lower boiling cut under mild conditions to convert the olefins and the higher boiling cut under severe conditions to improve its aromatic content, the operating temperature for the lower boiling cut being in the range of 750 to 825° F. and for the higher boiling cut in the range of 820 to 950° F., separating from the products of said cuts the hydrocarbons in the boiling range of aviation gasoline, and combining said segregated hydrocarbons.

3. In the production of aviation base stock the process steps of subjecting a crude hydrocarbon charge higher boiling than the desired aviation stock to a catalytic cracking operation, separating the products which have an end point of approximately 500° F. into two parts, the division being effected in the range of 125 to 225° F., removing olefins from the lower boiling part by a relatively mild catalytic cracking treatment, subjecting the higher boiling part to the action of high activity silicious cracking catalyst under severe operating conditions including low feed rate, temperature above 820° F. but not above 950° F., and superatmospheric pressure up to 150 lbs. per sq. in. gauge, and combining the products in the boiling range of aviation gasoline from both treating operations.

4. In the production of high quality aviation base stock the process of dividing a charge of cracked hydrocarbons having an end point of approximately 500° F. into two parts, the division being effected in the range of 125 to 225° F., subjecting the lower boiling cut to relatively mild catalytic treatment by high activity silicious cracking catalyst at superatmospheric pressure up to about 50 lbs. per square inch gauge in the temperature range of 750 to about 825° F. and at feed rates (liquid volume of charge per volume of catalyst per hour) of 1:1 to 3:1 to remove or to convert olefins, subjecting the higher boiling cut to relatively severe catalytic treatment by high activity silicious cracking catalyst at superatmospheric pressure up to about 150 lbs. per sq. in. gauge in the temperature range of 820 to 950° F. and at feed rates of 4:1 to 1:1, and combining the products in the boiling range of aviation gasoline from both treating operations to obtain aviation gasoline capable of meeting both lean mixture and rich mixture performance requirements.

5. Process as set forth in claim 4 in which the cracking catalysts comprise synthetically produced silica-alumina compounds of low alkali metal content with activity indexes of at least 35.

6. In the production of aviation base stock, the process comprising the steps of separating cracked gasoline having an end boiling point of the order of 450° F. to 500° F. into two parts, a lower boiling part having an end boiling point in the range of about 125° F. to about 210° F. and containing most of the olefins, and a higher boiling part concentrated in naphthenes and aro-

matics but having a low content of olefins, subjecting said lower boiling part to catalytic cracking treatment which increases its saturation by reducing its content of olefins, improving said higher boiling part by subjecting it to catalytic cracking conditions which are sufficiently severe, including use of active silicious cracking catalyst having activity index of at least 35, superatmospheric pressure, and temperature within the range of 820° F. to 950° F., to effect transformation of naphthenes and aromatics into hydrocarbons within the aviation gasoline boiling range having improved rich mixture performance characteristics, and combining products from both treating operations which are in the boiling range of aviation gasoline.

7. In the production of aviation base stock the process steps of separating cracked hydrocarbons having an end point of approximately 500° F. into two parts, the lower boiling part having an end boiling point and the higher boiling part an initial boiling point of approximately 200° F., reducing the olefin content of said lower boiling part by subjecting it to relatively mild catalytic cracking treatment, subjecting said higher boiling part to the action of a silicious catalyst of at least 35 activity index under severe cracking conditions, and combining the products of the operations on said lower boiling and higher boiling parts, which are in the boiling range of aviation gasoline.

8. In the production of aviation base stock the process steps of separating catalytically cracked hydrocarbons having an end point of approximately 500° F. into two parts, the lower boiling part having an end point and the higher boiling part an initial of approximately 200° F., converting olefins in said lower boiling part to saturates within the aviation gasoline boiling range by a relatively mild catalytic cracking treatment, subjecting said higher boiling part to the action of a synthetic silicious catalyst of low alkali metal content and of at least 35 activity index under severe cracking conditions, and combining the products of the operations on said lower boiling and higher boiling parts, which are in the boiling range of aviation gasoline.
